E. A. REID

TUBULAR FLAME OIL BURNER FOR CRUCIBLES AND OTHER USES

Filed Oct. 22, 1924

Patented May 4, 1926.

1,583,311

UNITED STATES PATENT OFFICE.

ERNEST ANDREW REID, OF LONDON, ENGLAND.

TUBULAR FLAME OIL BURNER FOR CRUCIBLES AND OTHER USES.

Application filed October 22, 1924. Serial No. 745,063.

To all whom it may concern:

Be it known that I, ERNEST ANDREW REID, a subject of the King of Great Britain, and resident of London, England, have invented 5 certain new and useful Improvements in Tubular Flame Oil Burners for Crucibles and Other Uses, of which the following is a specification.

This invention relates to tubular flame oil 10 burners for crucibles and other uses. Its object is to produce a circular or tubular flame extending upwardly within the flue from below the crucible's supporting means. Another object is to form the usual crucible 15 supporting bars as burner members and to make such burner member readily substituted for the ordinary, solid, crucible supporting bar.

In the accompanying drawings illustrating the invention and forming a part hereof,

Fig. 1 is a vertical, central section elevation at line 1—1 of Fig. 2 of a part of a crucible within a flue, mounted on the usual refractory material, which in turn is supported on the upper side of a transverse, crucible supporting bar, such bar, in the present case, being chambered to form a burner member.

Fig. 2 is a vertical, central sectional elevation at right angles to the line of a section 30 on which Fig. 1 is taken. Fig. 2 is a section corresponding to line 2—2 of Fig. 1 and also to line 2—2 of Fig. 3.

Fig. 3 is a top plan view of the burner.

Fig. 4 is a vertical, central elevation of the 35 burner enlarged, at line 4—4 of Fig. 3.

Fig. 5 is an end view of what is shown in Fig. 4.

Fig. 6 is a diagrammatic plan view of the jetting operation of my improved burner.

In the drawings, a horizontal burner member 40 has the form of the usual solid, crucible supporting bar. It is provided between its ends, on its upper side, with an upstanding lobe 2 on which refractory material 3 is mounted as a support for the upstanding crucible 4, which is shown enclosed with an ordinary flue A.

The bar 1 is provided between its ends with a lengthwise extending, atomizing fluid receiving chamber 5, the outer end of which is ported for connection with an atomizing fluid supply conduit 6. Chamber 5, at its inward end, is provided with an escape port 7 in communication with a dependent tube 8, the under end of which carries an atomizing fluid receiving atomizer 9 which extends

transversely of and is at right angles to the chambered bar 1. The under end of tube 8 is provided with a vertical flange 10, which is fastened to a vertical flange 11 of the atomizer 9. Pipe 8 is in communication through a port 12 with the chamber 13 of the atomizer 9 the ends of which project equally at each side of the bar 1. The atomizer 9 has a chambered casing and is shown provided 60 with plugs X, whereby the chamber may be readily cleaned out, when and if desired, especially when the atomizer is cast. The upper wall 14 of each upper end, corner portion of the atomizer casing 9 is transversely 65 depressed, as shown in Fig. 4, and each of these walls 14 is formed near the adjacent end wall of the casing 9 with a series of upwardly extending jet orifices 15. At a higher level than the jet orifices 15, the upper portion of each depressed wall 14 is formed 70 with a series of jet orifices 16, the axes of which are at uniform angles to the axes of the jet orifices 15. These jet orifices 15 and 16 are arranged in pairs in a vertical plane, 75 so that a jet from one orifice impinges directly upon a jet through the other orifice of the pair of orifices.

The bar 1 is also provided between its ends with a lengthwise extending, fuel oil 85 receiving chamber 17 the outer end of which is in ported connection with a fuel oil supply pipe 18. The inner end of chamber 17 is provided with a fuel oil escape port 19 which communicates with the upstanding, 90 intake port 20 of a fuel oil distributor casing 21, which is mounted above and parallel with the atomizer casing 9. The casing 21 is shorter than the casing 9 and has its ends 95 transversely cut out at 22 to form a fuel oil escape. The bottom 23 of casing 21 constitutes a film forming floor of the casing 21. Each end of this floor is turned downwardly into a film delivering lip 24. Each lip 24 extends transversely across the end 100 of the casing 21 and is positioned above a depressed wall 14 of the casing 9, so that an oil film is delivered over a lip 24 simultaneously at each end of the casing 21 and falls upon the intersections of the jets of atomizing fluid issuing from the adjacent jet orifices 15 and 16. Preferably, each lip is formed with end lobes 25 that project 105 downwardly below an intermediate portion of the under edge of the lip. The end lobes 25 insure the formation of the thin oil curtain across the full width of the lip, corre-

spondingly to the length of each row of jet orifices 15 and 16.

The tubular flame F, shown in Fig. 1, is effected by the suction of the upward draft through the flue A. It heats the crucible at the bottom thereof equally and causes a simultaneously heating effect of the flame entirely around the crucible. Heretofore crucibles have been heated unequally by a spiral flame impinging upon a side of the crucible at the upper portion thereof. The unequal heating of crucibles, has heretofore resulted in frequent cracking of the crucibles.

15 A great advantage of the present burner for use in connection with crucibles or the like, is that the flame initially effected in each field of atomization at an end of the combined casings 9 and 21, is so removed 20 from the sides of the chambered bar 1 that the bar is not raised to a destructive heat and becomes a substantially permanent member of the atomizing burner, the other members of which are of a permanent construction.

The jetting orifices being arranged in pairs having their axes in a vertical plane, establish at approximately 45° from the horizontal a series of overlapping zones γ 30 of atomization, free from interstices, through which oil from the oil curtain could drop and result in carbonization, as illustrated in Fig. 6, whereas when the jets are arranged in upper and under horizontal pairs, as in my said patent, there is no such an overlapping of zones of atomization as to preclude the formation of such interstices and such interstices are formed at α adjacent the 35 points of intersection of the jets from each pair of horizontal jet orifices.

40 The bar 1 spans the under, open end of the flue A within which the crucible is mounted. The flue is provided with brackets a having horizontal portions through which bolts a' pass downwardly through openings a^2 in the end extensions a^3 of the bar 1. Thus the chambered bar is readily detachable; and can be readily substituted for solid bars heretofore used for supporting 45 the crucibles.

50 In the burner shown in said earlier patent and also according to the present invention, the fuel oil is distributed in the form of a film which falls over a transverse lip as a thin curtain in front of a plurality of converging jets of atomizing fluid under pressure the oil film or curtain extending theoretically and generally in practice, the whole transverse width of the burner lip.

55 An advantage of said patented burners and of the present improved burner is that, owing to the fact that the velocity of the atomizing fluid is minimized by the impinging of one jet on the other, and further 60 by the dropping of the film of fuel oil on

the point of collision of the jets, the atomized mixture of fluid and fuel or combustible product enters a furnace on which the burner is installed with a very low velocity, providing thereby the necessary 70 element of time for a thorough and early admixture of the necessary oxygen to insure immediate and perfect combustion of the atomized fuel to CO_2 with the result that a short and intense, well-distributed 75 and even flame is produced. The time element which this burner introduces is one of the features characterizing the working of this burner. It is found in practice that 80 practically smokeless combustion is produced if the fuel oil and atomizing fluid supply are correctly adjusted.

It has been found in actual practice that with burners provided with the atomizing jets with their axes of impingement in a 85 vertical plane instead of in the horizontal plane oil does not drop through the stream of atomizing fluid. This is owing to the fact that the zone of dispersed atomization, due to each pair of jets, is at right angles to their 90 axes of impingement, the dispersion zone formed by one pair overlapping that produced by the neighboring pair of jets and forming thereby a complete and continuous 95 zone of dispersed atomization, which does not permit the dropping through the zone of dispersed atomization of the fuel. If this occurred, it would cause trouble in operation by the oil dropping on to the floor of the 100 furnace and carbonizing there. In order to effect this action, it will be noted that with jets impinging with their axes horizontally, the zones of dispersion will be vertical, and it is practically inevitable that in this way 105 interstices will be formed between adjacent zones of dispersion, and fuel will be apt to drop through. The complete and satisfactory 110 combustion of the fuel oil in a burner with the atomizing jets, located one above the other and with their axes of impingement vertical, is further assured by the construction given to the lower edge of the lip of the burner which is formed with an irregular edge, so that the oil, due to its 115 viscosity and surface tension produced, maintains a film of practically even thickness the whole width of the burner, insuring thereby the even working of the atomizing fluid and the production of an entirely even and well dispersed flame; securing also a 120 uniform distribution of heat in the boiler or furnace or object to be heated.

The overlapping zones γ of atomization extend slantingly upwards in the tubular frame produced by the burner.

What I claim is:

1. As a new article of manufacture, a fuel oil, tubular flame burner comprising a bar chambered for reception and discharge of fuel oil; a casing having a fuel oil receiving 125

chamber, and a casing having a therewith alined atomizing fluid receiving chamber; the fuel oil receiving chamber having openings at each end and an oil film supporting bottom wall terminating in a dependent, transverse, oil discharge lip at each said opening; and the atomizing fluid receiving chamber having at each end a transverse wall spaced apart from and located below one of said lips; said wall being provided with an upper series and also with an under series of jet orifices; said casings being in parallelism one with another and mounted crosswise of said chambered bar; and each 15 lip and the therewith associated jet orifices being spaced apart from a side of the bar.

2. As a new article of manufacture, a fuel oil, tubular flame burner comprising a bar chamber for reception and discharge of fuel oil; a casing having a fuel oil receiving chamber; and a casing having a therewith alined, atomizing fluid receiving chamber; the fuel oil receiving chamber having openings at each end and an oil film supporting bottom wall terminating in a dependent, transverse, oil discharge lip at each said opening; and the atomizing fluid receiving chamber having at each end a transverse wall spaced apart from and located below one of said lips; said wall being provided with an upper series and also with an under series of jet orifices; said casings being in parallelism one with another and mounted crosswise of said chambered bar; and each 25 lip and the therewith associated jet orifices being spaced apart from a side of the bar; each of said lips having dependent end lobes.

3. A fuel oil tubular flame burner comprising a bar chambered for reception and discharge of fuel oil; a casing having a fuel oil receiving chamber; and a casing having a therewith alined atomizing fluid receiving chamber; the fuel oil receiving chamber having openings at each end and an oil film supporting bottom wall terminating in a dependent, transverse, oil discharge lip at each said opening; and the atomizing fluid receiving chamber having at each end a 40 transverse wall spaced apart from and lo-

cated below one of said lips; said wall being provided with an upper series and also with an under series of jet orifices; said casings being in parallelism one with another and mounted crosswise of said chambered bar; and each lip and the therewith associated jet orifices being spaced apart from a side of the bar; all in combination with an upstanding flue; within the flue an upstanding crucible supported on said bar, the bar spanning the under side of the flue to permit discharge of the flame upwardly and tubularly around the crucible. 45

4. A fuel oil burner having a lengthwise extending, atomizing fluid receiving and discharge chamber, a lengthwise extending, fuel oil receiving and discharge chamber; communicating with said atomizing fluid receiving and discharge chamber, a casing mounted crosswise of said chambered bar 50 and provided at each end with jet orifices; and, communicating with said fuel oil receiving and discharge chamber, a casing provided at each end with an oil film discharge lip spread apart from and located to discharge upon jets issuing from the therewith associated jet orifices. 75

5. A fuel oil burner having a lengthwise extending, atomizing fluid receiving and discharge chamber, a lengthwise extending, fuel oil receiving and discharge chamber; communicating with said atomizing fluid receiving and discharge chamber, a casing mounted crosswise of said chambered bar 80 and provided at each end with jet orifices; and, communicating with said fuel oil receiving and discharge chamber, a casing provided at each end with an oil film discharge lip spread apart from and located to discharge upon jets issuing from the therewith associated jet orifices. 85

Signed at New York city, in the county of New York and State of New York, this 16th day of October A. D. 1924. 90

ERNEST A. REID.
